United States Patent Office

Des. 227,933
Patented July 24, 1973

227,933

SORTER FOR A DUPLICATING MACHINE OR THE LIKE

Stephen K. Bright, Fairport, N.Y., assignor to Xerox
Corporation, Stamford, Conn.

Filed May 27, 1971, Ser. No. 147,722

Term of patent 14 years

Int. Cl. D18—99

U.S. Cl. D64—11 B

FIG. 2

FIG. 3

FIG. 4

FIG. 6

FIG. 5

FIG. 1 is a front perspective view of a sorter for a duplicating machine or the like showing my new design; FIG. 2 is a front elevational view thereof;

FIG. 3 is a rear elevational view thereof;

FIG. 4 is a top plan view thereof;

FIG. 5 is a right side elevational view thereof; and

FIG. 6 is a left side elevational view thereof.

I claim:

The ornamental design for a sorter for a duplicating machine or the like, as shown.
